METHOD OF FORMING CONCRETE WALLS

William Allen Jennings, Des Moines, Iowa, assignor to Economy Forms Corporation, Des Moines, Iowa, a corporation of Iowa

Application May 29, 1936, Serial No. 82,473

1 Claim. (Cl. 25—154)

The object of my invention is to provide a double monolithic concrete wall containing between the two walls both moistureproofing material and heat insulating material and being so constructed that the movement of either of the walls by contraction or expansion, due to changes in temperature, will not be transmitted to the other wall to thereby reduce the probability of cracking due to such expansion and contraction.

A further object is to provide a method of constructing my improved wall at a minimum of expense for labor and material.

In the accompanying drawing Figure 1 shows a sectional view of a single concrete wall with two metal forms on its sides.

Figure 2 shows a similar view with one of the metal forms removed and the spreader bar supported in the concrete.

Figure 3 shows a sectional view of the completed double monolithic wall with the moistureproofing and insulating material applied and with the metal forms on the outer surfaces of the walls.

Figure 4 shows a view similar to Figure 3 with the forms removed; and

Figure 5 shows a view of the completed wall with a wooden wall supported by the concrete wall.

In the construction of my improved wall I preferably employ sheet metal mould forms of the kind now in common use and which have smooth sheet metal body portions 10 braced and reinforced by outwardly extended flanges 11, which flanges are provided with holes 12 to receive pins 13, and I also employ spreader bars 14 to extend through openings formed in both of the forms and provided with two openings 15 at one end through which the pins 13 may be extended.

I practice my improved method as follows: I first erect the two forms in spaced apart position and, as is customary, each form structure is suitably braced and supported to hold it in position. Then in the space between the forms the first concrete wall is erected in the ordinary manner. This wall is indicated as 16. I then remove the mould forms from one side of the concrete wall after the wall has set and hardened. This leaves the spreader bars 14 projecting out through the exposed surface of the wall. I then apply to the exposed surface of the wall a coating of moistureproofing material 17, such for instance as asphalt paint, which has the characteristic that when contained between two concrete walls, as

is done in my improved method, it will remain in plastic condition, and it is also characterized by being of a sticky or adhesive nature. I then utilize this moistureproofing material as a means for temporarily supporting a layer of heat insulating material 18. In some instances I employ as the heat insulating material the well known product mineral wool, and this is applied by simply pressing it against the sticky or adhesive moistureproofing material. I have also employed wall boards made of corn stalks or the like, and this also is supported in position by the sticky or adhesive moistureproofing material. I then preferably apply another coating of the same moistureproofing material to the opposite side of the insulating material. I then replace the form structure previously removed, by simply mounting it upon the projecting spreader bars which are extended through openings in the form and then securely locked against movement by the pins 13 extended through the outer one of the holes 15. This is done after the first wall has set and hardened and the form is securely held in place by the spreader bars and pins so that it is not necessary to use braces for supporting the form at this time.

Then the second concrete wall is poured in the space between the first wall and the replaced form.

After the second wall is set and hardened I remove the spreader bars. These are straight and uniform in size throughout and can easily be thus withdrawn. I find that in practice when these spreader bars are removed before the removal of the forms, their removal does not cause the concrete surrounding the spreader bars to chip off to any appreciable extent. When the spreader bars are removed, the form sections are also removed, and after such removal the openings in the concrete wall from the outer side are filled with moistureproofing material 19, and I preferably fill the openings at the inner side of the wall with wooden plugs 20 which I have found to be convenient for nailing wooden strips 21 to the concrete wall so that a wooden wall 22 could be supported against the concrete wall when desired.

I also preferably employ tie wires 23 preferably made of somewhat flexible metal, one end of which is inserted through the mould form before the first concrete wall is poured, and then when the form is removed for pouring the second concrete wall, these tie wires are bent outwardly into the space for the second concrete wall, thus firmly uniting the walls together.

By the use of my improved method I have

found that a great deal of labor and material is saved because, after the first wall has set and hardened, the forms may be very quickly and easily replaced in position and supported by the spreader bars which are firmly fixed in the first concrete wall, so that the material and labor necessary to brace and support the replaced forms can be saved.

I have also found that with my improved double monolithic concrete wall the cracking of the walls due to expansion and contraction by temperature changes is almost wholly eliminated because, with the moistureproofing material in plastic condition one wall may be moved slightly in the manner in which it is moved by contraction or expansion without imparting a corresponding motion to the other wall, because the plastic moistureproofing material permits slippage of one wall relative to the other.

I claim as my invention:

The method of constructing upright concrete

walls, which consists in providing two upright mould forms, supporting said mould forms in spaced apart positions by spacing bars extended through and beyond one of the mould forms, then filling the space between the mould forms and permitting it to set and harden and thereby firmly hold the spacing bars in position, then removing the mould form through which the spacing bars are extended, then applying a layer of compressible material to the exposed concrete surface, then replacing the mould form upon the spacing bars in spaced apart position from the compressible material and utilizing the previously formed concrete wall in firmly holding the spacing bars and supporting the replaced mould form, then filling the space between the compressible material and the replaced mould form with the concrete and removing the mould forms and spacing bars.
